CONTAINER FOR LIQUIDS

Richard L. Platte, Ann Arbor, Mich., assignor to Hoover
Ball and Bearing Company, Saline, Mich.

Filed Apr. 12, 1965, Ser. No. 84,721

Term of patent 14 years

(Cl. D58—17)

FIG. 1

FIG. 2

FIG. 3

FIG. 4

FIG. 5

FIG. 6

FIG. 7

FIGURE 1 is a perspective view of a container for liquids showing my new design;

FIGURE 2 is an enlarged top plan view thereof;

FIGURE 3 is an enlarged side elevational view thereof;

FIGURE 4 is an enlarged front elevational view thereof;

FIGURE 5 is an enlarged rear elevational view thereof;

FIGURE 6 is a fragmentary section taken on the lines 6-6 of FIG. 2; and

FIGURE 7 is a fragmentary sectional view taken on the lines 7-7 of FIG. 2.

The essential feature of my design resides in the portions of the drawings shown in full lines.

I claim:

The ornamental design for a container for liquids, substantially as shown and described.
